FLEXIBLE STAYBOLT CONSTRUCTION FOR
BOILERSJulius Kindervater, Richmond, Va., assignor to
American Locomotive Company, New York,
N. Y., a corporation of New York

Application May 20, 1939, Serial No. 274,716

4 Claims. (Cl. 85—1.5)

This invention relates to flexible staybolt construction for boilers.

The present invention is an improvement upon the flexible staybolt construction of Patent No. 5 2,028,474, issued to G. P. Robinson January 21, 1936.

The object of the invention is to provide a pressure-applying flexible means between the sleeve closure and diaphragm that seats upon 10 the head end of the bolt.

Other and further objects of and advantages achieved by the present invention will be apparent from the following description of an approved embodiment thereof and the claims appended hereto.

Referring to the drawing forming a part of this application, Figure 1 is a central longitudinal sectional view of a staybolt construction embodying the present invention secured to the 20 boiler sheets fragmentally shown in section, the bolt being shown in elevation; and Fig. 2 is a top plan view of the staybolt assemblage.

The staybolt proper 1 is screwed into the inner boiler sheet 2, the extending end 3 of the bolt being flanged over against the adjacent face of the sheet 2. The bolt, at its opposite end, is provided with a head 4 having its face spherically shaped and a projection 5 extending beyond the head and provided with a spherically-shaped face 6. The faces of the head 4 and projection 5 are preferably formed of portions of spheres having a common center X. The bolt is provided with a tell-tale hole 7 extending through the bolt from end to end thereof and slots 8 for the application of a tool to facilitate screwing the bolt into the inner boiler sheet in the usual manner.

The outer boiler sheet 9 is provided with a 40 conically shaped orifice in which is seated the sleeve 10 secured to the sheet 9 by a weld 11.

A cover 12 is provided for the outer end of the sleeve. The cover is secured to the sleeve, the sleeve having external threads 13 and the cover 45 having internal threads 14 providing means for screwing the cover upon the sleeve. The sleeve and cover provide a housing for the head end of the bolt. The cover is provided with a seat 15 for a purpose later to be described.

50 In the preferred embodiment a composite cover is employed comprising a cap 16 which is provided with the internal threads 14 and the seat 15 and a plug 17. The plug is secured in an orifice in the cap. The cap is provided with internal threads 18 and the plug with external threads

19 providing means for screwing the plug into the cap.

The plug is provided with a hole 20 in line with the hole 7. The hole 20 has angular walls 21 and the cap has angular walls 22, each for the application of a suitable tool for applying them and removing them respectively from the cap and sleeve, the respective threaded connections permitting adjustment of the plug relative to the cap and the cap relative to the sleeve.

10 A cup-shaped diaphragm 23 extends across the housing and is secured at its outer periphery to the wall thereof. In the present instance the diaphragm at the outer margin of the cap is provided with a flange 24 which is engaged by 15 the seat 15. The central portion 25 of the diaphragm engages the spherically-shaped face 6 and is conformed correspondingly thereto.

The invention is confined to a flexible staybolt but not to any particular construction. The 20 construction shown for illustrative purposes is similar to that of the aforesaid Robinson patent, and as thus far described is similar in all respects to that of the Robinson patent except as to the plug. The plug of the Robinson patent 25 has external angular faces for the application of a tool whereas in the present instance the plug has internal angular faces, but it will be understood that in this respect the Robinson plug may be followed. Nevertheless the internal 30 angular faces enable the plug to be made shorter and thereby save space that may in some instances be important. In the Robinson patent the plug has a projection extending to and engaging the central portion 25 of the diaphragm. 35 In the present instance the plug has no such projection, but instead resilient means is disposed between the plug and the central portion of the diaphragm comprising a washer 26 which 40 seats upon the central portion of the diaphragm and is conformed, at its seating face, to the shape thereof. Opposite to this face the washer is provided with a flange 27. The resilient means further comprises a split spring washer 28 disposed between the washer 26 and the plug 17 45 encircling the flange 27. Other resilient elements may be substituted for the washer 28, as for instance a coil spring. The washers and diaphragm portion are orificed to provide communication between the holes 20 and 7. 50

The split washer 28, which is backed by the plug 17, yieldingly presses upon the washer 26 which in turn presses upon the central portion of the diaphragm thereby producing a tight fit between the central portion and the bolt en- 55

gaged thereby. As the split washer 28 is resilient, it provides a flexible connection between the diaphragm central portion and the bolt. The bolt is of the flexible type. Therefore as it flexes in service it is permitted to slide freely relative to the diaphragm due to the flexible connection, and furthermore to move away from its seat in the sleeve against the pressure of the split washer should occasion arise for such movement.

The split washer insures the tight fit between the diaphragm portion and bolt as the working parts become worn, the split washer expanding to compensate for such wearing. The plug 17 may be adjusted to tension the split washer to the necessary extent to produce the required pressure between the diaphragm portion and bolt to prevent leakage. To this end there is preferably a free or loose threaded engagement between the 20 plug and cap, that is to say the plug does not bind in the cap. There is thus a tendency for the plug to work loose, thus destroying the desired adjustment for providing the necessary tensioning of the split washer. The split washer thus serves 25 another purpose, namely by being backed by the washer 26 it reacts to press against the plug and to thereby lock it in its adjusted position.

In many instances staybolts are sold to locomotive builders who assemble the staybolts with 30 the locomotive. It is therefore desirable to provide as few loose parts as possible, not only to prevent loss of such parts but furthermore to prevent a wrong assembling of them. Therefore in the present instance the composite cover preferably, besides including the cap and plug also includes the diaphragm and the two washers all 35 assembled ready for screwing the plug upon the sleeve. To this end the flange 24 is secured to the cap thereby retaining the two washers in 40 proper relation between the diaphragm and plug. This is preferably accomplished by the employment of a washer 29 of pre-frusto-conical shape, such as is shown in the patent to Landgraf, No. 1,507,840, September 9, 1924. This is placed 45 against the flange 24 and pressed flat in the usual manner, firmly expanding its outer edge in gripping engagement with the cylindrical wall of the cap adjacent the seat 15. The washer 29, when 50 the cap is screwed upon the sleeve, seats upon the outer end of the sleeve and, by screwing the cap tightly, seals the joint between the sleeve and the cap.

While it has been stated that the spherically-shaped face of the head of the bolt engages the 55 correspondingly shaped seat in the sleeve, it will be understood that the invention also covers a flexible bolt construction of the type shown for instance in the reissue patent to Mennie, No. 14,796, January 27, 1920, Fig. 2 thereof, wherein 60 the seat for the bolt head is formed in the boiler sheet instead of in the sleeve, and the sleeve is seated upon the outer face of the boiler sheet and welded thereto, and the appended claims are intended to include such a type of flexible staybolt unless otherwise limited. Furthermore, while a welded-on sleeve is employed, it will be understood that a threaded-on sleeve or any other appropriate sleeve may be used, if desired.

While there has been hereinbefore described 70 an approved embodiment of this invention, it will be understood that many and various changes and modifications in form, arrangement of parts and details of construction thereof may be made without departing from the spirit of the invention 75 and that all such changes and modifications as

fall within the scope of the appended claims are contemplated as a part of this invention.

The invention claimed and desired to be secured by Letters Patent is:

1. A staybolt construction comprising a housing 5 formed of a sleeve having a seat, and a cap secured to said sleeve and provided with an opening; a staybolt having a head in flexible engagement with said seat and a longitudinal hole open at the head end; a plug secured in said cap opening, having a hole extending therethrough open at the outer end to the exterior; a diaphragm extending across said housing with its outer periphery sealed to the wall of said housing and its central portion engaging said staybolt; and resilient pressure-applying means disposed between and in engagement with said plug and said diaphragm portion, said diaphragm portion and said means being orificed affording communication between said holes, and said 20 means pressing against said diaphragm portion thereby holding said diaphragm portion tightly against said staybolt, providing a flexible connection between said diaphragm portion and said staybolt. 25

2. A staybolt construction comprising a housing 30 formed of a sleeve having a seat, and a cap secured to said sleeve and provided with an opening; a staybolt having a head in flexible engagement with said seat and a longitudinal hole open at the head end; a plug secured in said cap opening, having a hole extending therethrough open at the outer end to the exterior; a diaphragm extending across said housing with its outer periphery sealed to the wall of said 35 housing and its central portion engaging said staybolt; and pressure-applying means disposed between said diaphragm portion and said plug, including a washer engaging said diaphragm portion and a resilient element disposed between 40 and operatively engaging said washer and said plug for applying pressure to said washer for holding said diaphragm portion tightly against said staybolt, providing a flexible connection between said diaphragm portion and said staybolt, 45 said diaphragm portion, said washer and said element being orificed affording communication between said holes.

3. A staybolt construction comprising a housing 50 formed of a sleeve having a seat, and a cap secured to said sleeve and provided with an opening; a staybolt having a head in flexible engagement with said seat and a longitudinal hole open at the head end; a plug secured in said cap opening, having a hole extending therethrough open 55 at the outer end to the exterior; a diaphragm extending across said housing with its outer periphery sealed to the wall of said housing and its central portion engaging said staybolt; and pressure-applying means disposed between said 60 diaphragm portion and said plug, including a washer engaging said diaphragm portion and a split spring washer disposed between and operatively engaging said first mentioned washer and said plug for applying pressure to said first mentioned washer for holding said diaphragm portion tightly against said staybolt, providing a flexible connection between said diaphragm portion and said staybolt, said diaphragm portion and said washers being orificed affording communication between said holes. 70

4. The combination of a headed staybolt; a housing for the headed end of said staybolt, said housing comprising a sleeve in which the end of said staybolt projects, said sleeve being adapt- 75

ed to be tightly secured to the wall of a boiler, and a cap secured to said sleeve and provided with a hole open to the exterior, and said staybolt having a rounded end in said housing spaced from the inner face of said cap and a hole opening therethrough; a diaphragm extending across said housing with its outer periphery sealed to the wall of said housing, its central portion being rounded corresponding to the rounded staybolt end and fitting thereupon; and pressure-applying means disposed in the space between said staybolt end and said cap, including a washer having a face forming a seat spaced from said

cap inner face and having an oppositely disposed rounded face corresponding to the rounded face of said diaphragm and fitting thereupon, and a compressed spring member disposed in the space between said washer and cap and bearing against said washer seat and cap inner face providing thereby a flexible pressure connection between said diaphragm portion and said staybolt end, said diaphragm portion, said washer, and said spring member being orificed affording communication between said holes. 5 10
